UNITED STATES PATENT OFFICE.

JOSEPH GORINAC, OF COLLINWOOD, OHIO.

LIQUID CONTAINER.

1,404,021.

Specification of Letters Patent. Patented Jan. 17, 1922.

Application filed February 2, 1921. Serial No. 441,870.

To all whom it may concern:

Be it known that I, JOSEPH GORINAC, a citizen of Jugoslavia, residing at Collinwood, in the county of Cuyahoga and State 5 of Ohio, have invented certain new and useful Improvements in Liquid Containers, of which the following is a specification.

This invention relates to certain new and useful improvements in liquid containers 10 and has particular reference to a container in the form of a drinking glass or goblet of double wall construction containing a colored liquid between the walls to create the impression that the container is filled with 15 liquid and also is embodied in the form of a bottle having separate compartments containing liquids of different colors.

The primary object of the invention is to 20 provide a liquid container in the form of a glass or goblet for amusement purposes wherein the container is of double wall construction with a plug closed opening in the outer wall for receiving a colored liquid to 25 fill the space between the walls of the container.

A further object of the invention is to 30 provide a liquid container in the form of a bottle especially designed for display purposes for use in drug stores and the like 35 wherein the container is formed of independent compartments adapted to be filled with differently colored liquids with a central prismatic tubular section containing illuminating means to render the liquids 40 translucent.

With the above and other objects in view, 45 the present invention consists in the novel form, combination and arrangement of parts hereinafter more fully described and shown 50 in the accompanying drawings, in which like reference characters indicate similar parts throughout the several views.

In the drawings,

Figure 1 is a vertical sectional view of the 55 liquid container bottle constructed in accordance with the present invention, showing the independent compartments therein for containing liquids of different colors.

Figure 2 is a horizontal sectional view 60 taken on line II—II of Figure 1 showing the filling tubes for the separate compartments,

Figure 3 is a vertical sectional view of a 65 double walled goblet constructed in accordance with this invention showing the closure 70 plug for the space between the walls, and

Figure 4 is a vertical sectional view of a double walled glass showing the closure plug 75 for the space between the walls.

Referring more in detail to the accompanying drawing and particularly to Figures 1 and 2, there is illustrated a liquid containing bottle of oval formation embodying 80 a wall 1 having a neck 2 with the throat of the bottle open and a plug stopper 4 entering the neck 2.

The interior of the bottle 1 is divided into upper and lower compartments 5 and 6 respectively and an intermediate compartment 7 by the provision of spaced horizontal partitions 8 and 9. A tubular member 10 is arranged centrally of the bottle 1 and is closed 85 at its upper end as at 11 while the lower end 12 is opened and is in the same plane as the lower end of the bottle, the wall of the bottle, the partitions 8 and 9 and the tubular 90 member 10 preferably being of integral construction as illustrated and formed of glass or other transparent material. The inner face of the tubular member 10 is formed with prismatic surfaces 10^a and an electric 95 lamp 13 is disposed within the tubular member 10 as illustrated in Figure 1 and connected with a suitable source of electric current for illuminating the lamp. The compartments 5, 6, and 7 are filled with differently colored liquids, the compartment 7 being 100 in communication with the tube 14 closed at its lower end by a screw plug 15 while the compartment 5 is in communication with the tube 16 closed at its lower end 105 by a screw plug 17. The lower compartment 6 is filled through the opening 18 shown in Figure 2 which is closed by a plug similar to the plugs 15 and 17. It will therefore be seen that the compartments are non- 110 communicative and are filled through independent openings closed by separate plugs so that liquids of different colors may be placed in the several compartments. When so filled, the lamp 15 may be illuminated and the bottle displayed for advertising purposes with the liquids illuminated and rendered translucent, thus presenting an attractive and pleasing appearance.

In the construction shown in Figure 3, the invention 105 embodies a goblet including a tubular stem 19 supported on a base 20 and having a goblet bowl 21 at the upper end thereof with an inner wall 22 closed at its lower end as at 22^a and formed integral with the upper end 110

of the bowl 21 with the wall 22 spaced from the wall 21. The upper end of the tubular stem 19 is closed by a screw plug 23 and a colored liquid between the walls 21 and 22 5 will create the impression of the inner wall of the goblet containing a liquid.

In the form of the invention shown in Figure 4, a drinking glass or tumbler is disclosed, the same embodying an outer wall 24, 10 connected to the bottom wall 25 having a central opening therein closed by a screw plug 26 while a tapering inner wall 27 connected at its upper end to the upper end of the wall 24 is spaced from the side wall 24 15 and the bottom wall 25. A liquid is placed between the walls 24 and 27 and amusement is obtained by persons attempting to empty or drink the fluid contents which is sealed between the spaced walls.

20 While there are herein shown and described the preferred embodiments of the invention, it is nevertheless to be understood that minor changes may be made in the form, combination and arrangement of parts without departing from the spirit and 25 scope of the invention as claimed.

What is claimed as new is:

1. A liquid container comprising a body wall, spaced partitions in said container dividing the same into separate compartments, 30 an independent filling tube associated with each compartment, a closure plug for the outer end of each filling tube and a central tubular member within the container having prismatic surfaces formed on the inner 35 face thereof.

2. A liquid container comprising a body wall, spaced partitions in said container dividing the same into separate compartments, 40 an independent filling tube associated with each compartment, a closure plug for the outer end of each filling tube, a central tubular member within the container having prismatic surfaces formed on the inner face thereof and an electric lamp disposed within 45 the tubular member.

In testimony whereof I affix my signature in presence of two witnesses.

JOSEPH GORINAC.
